HEMO DIALYSIS MACHINE

C. Edwin Schmidt, 1672 Summerville,
Tustin, Calif. 92680

Filed Oct. 3, 1973, Ser. No. 403,234

Term of patent 14 years

Int. Cl. D24—02

U.S. Cl. D83—1 F

FIG. 1

FIG. 2

FIG. 3

FIG. 4

FIG. 5

FIG. 6

FIG. 1 is a perspective view of a hemo dialysis machine showing my new design;

FIG. 2 is a view in elevation of one end of the machine;

FIG. 3 is a view in front elevation of the machine;

FIG. 4 is a view in rear elevation of the hemo dialysis machine;

FIG. 5 is a top plan view; and

FIG. 6 is a bottom plan view of the machine.

I claim:

The ornamental design for a hemo dialysis machine, substantially as shown and described.
